UNITED STATES PATENT OFFICE

2,656,042

CENTRIFUGAL WASHING AND DRYING
MACHINE

Peter Eduard Geldhof and Luther Ringer, St. Joseph, Mich., assignors to Whirlpool Corporation, a corporation of New York

Original application June 21, 1943, Serial No. 491,618. Divided and this application September 8, 1947, Serial No. 772,630

1 Claim. (Cl. 210—63)

1

This invention relates to an automatic washing, rinsing and drying machine, and more particularly, to means for reducing vibrations in any centrifugal washing or drying machine.

This application is a division of our copending application for "Automatic Washing, Rinsing, and Drying Machine," U. S. Serial No. 491,618, filed June 21, 1943, and now Patent No. 2,521,159 and assigned to the same assignee as the present invention.

The development of satisfactory automatic washing, rinsing and drying machines for home use has been handicapped to some extent by the relatively great amount of vibrations usually associated with commercial laundry machines. Accurate dynamic balancing of large rotating masses, and particularly, unbalanced loads caused by non-uniform location of the clothes in the clothes container has been heretofore costly. For that reason, most automatic washing, rinsing and drying machines have either been high in price for the average home use, or else were of such a character that excessive vibrations were present.

One of the principal features and objects of the present invention is to provide novel means for reducing vibrations in centrifugal washing and drying machines, and particularly, machines for home use.

A further object of the present invention is to provide an automatic washing, rinsing and drying machine of novel design.

A still further object of the present invention is to provide a novel tub construction for a laundry machine.

Another and further object of the present invention is to provide a novel supporting structure and tub arrangement for a laundry machine.

Still another and further object of the present invention is to provide novel means for introducing liquid into the tub.

The novel features which we believe to be characteristic of our invention are set forth with particularity in the appended claim. Our invention itself, however, both as to its organization, manner of construction and method of operation, together with further objects and advantages thereof may best be understood by reference to the following description taken in connection with the accompanying drawings, in which:

Figure 1 is an elevation of a washing machine with parts of the cabinet removed to illustrate the operating relationship of the several parts of the apparatus and embodying the novel teachings and principles of the present invention;

2

Figures 2 and 3 together form a vertical section through the machine of Figure 1, Figure 2 being the upper portion of the machine with parts broken away, and Figure 3 being the lower portion of the machine with parts in elevation and broken away;

Figure 4 is a plan view with the top of the cabinet removed and part of the tub broken away to assist in demonstrating the orientation of the several parts of the apparatus and to illustrate the mounting for the tub;

Figure 5 is a partial elevation with parts broken away of the supporting member by means of which the tub and associated operating mechanism of the washing machine are flexibly supported from the cabinet;

Figure 6 is a partial sectional view illustrating the means for supplying the cleansing fluid to the apparatus at the upper end thereof directly through the vibration dampening means; and

Figure 7 is a partial elevation of a portion of the interior of the washing machine to show the outlet end of the fluid supply means of Figure 6.

Referring first to Figures 1 to 4 of the drawings, the automatic washing, rinsing and drying machine illustrated therein has had its exterior shell or cabinet removed for better inspection of the various component parts of the machine.

The principal frame structure embodies four corner posts 21 to each of which is secured an end of the upper channel members 22 and the lower angle members 23. The channels 22 and the angles 23 may be secured in any suitable fashion to the vertical posts 21, but are preferably welded to the posts 21.

The vertical legs of the angles 23 are cut away short of the ends of said angles and extend inwardly along the support legs 21 for a short distance. The horizontal legs of the angles 23 extend beyond the ends of vertical legs thereof and are cut away to conform to the arcuate forms of the inner peripheries of the support legs 21. The projecting ends of the angles 23, 23 form arcuate segments 24 and 25 at opposite ends thereof. The segments 24 and 25 of the adjacent angles 23, 23 overlie each other and are suitably secured together and to the inner peripheries of the legs 21, 21. The overlapping ends 24 and 25 of the angles 23 are apertured to receive bolts 26 forming a part of the foot 27, which is secured to said overlapping ends of said angles by means of a nut 28 (Fig. 3).

On the underside of the horizontally disposed flanges of the angles 23 of the frame structure are secured the angle members 29 as will be seen in Figures 1 and 3 of the drawings. The lower-

most edges of each of the several panels 18, 19 and 20 may be demountably attached to the angle members 29 in any suitable conventional manner.

A cover 30 is provided for the cabinet (see Figure 2) which has a downwardly extending flange portion 31 to provide a snug fit between the cover 30 and the panels 18, 19 or 20, as the case may be. The cover 30 may be secured to the frame in any suitable fashion, but is provided on the underside thereof with a pair of locating means which takes the form of the bent strips 32 secured to the underside of the cover 30 and adapted to register with a plurality of blocks 33 of some suitable resilient material so as to render the fit of the cover 30 with respect to the remainder of the cabinet tight and free from vibration.

Substantially all of the operating and control mechanism of the automatic washing machine 20 are supported within the cabinet on a sub-base 34 which is preferably in the form of a casting or spider and which is suspended from the frame structure in a manner which will presently be described.

Mounted on the upper side of the spider or sub-base 34 is the tub 35 which comprises a substantially cylindrical wall 36 and a base portion 37 secured to the spider 34 as by means of bolts 38. This tub 35 is centrally apertured to permit 30 the generally cylindrical boss portion 39 of the spider to pass therethrough. An annular shoulder 40 encircling the base of the cylindrical boss 39 cooperates with the gasket 41 and the ring 42 secured to the shoulder 40 as by means of bolts 43 to prevent leakage of the cleansing fluid from the aperture in the base 37 of the tub 35 which accommodates the boss 39. The boss 39 of the spider 34 is provided with a bore 44 in which is suitably secured a vertically extending, generally cylindrical center post 45.

The center post 45 is provided adjacent its uppermost end with a sleeve bearing 46 which is press fitted into the counterbore 47 of the internal bore of the center post 45. A hollow shaft 48 is journaled at its uppermost end in the sleeve bearing 46 for rotation in concentric relation to the axis of the center post 45. Disposed about the hollow shaft 48 and adjacent its uppermost end is a collar 49 which may be press fitted or otherwise suitably secured to the hollow shaft 48. The collar 49 is provided with a lower tapered portion 50 which serves as a mounting for the supporting member 51 in the upper end of which is inserted a sleeve 52, the internal contour of which corresponds to the tapered portion 50 of the collar 49.

A retaining ring 53 is threaded onto the upper end of the collar 49 and is provided with a tapered portion 54 at its lowermost end which engages the upper end of the sleeve 52 so as to force it against the tapered portion 50 of the collar 49. The lower end of the supporting member 51 is flared outwardly so as to encircle the uppermost end of the boss 39 of the spider 34. The supporting member 51 serves as a mounting for the perforated extractor basket 55 which is secured thereto in any suitable fashion adjacent the flared end thereof. The basket 55 is provided with an opening 56 in the uppermost end thereof and a plurality of perforations 57 in the generally cylindrical wall and the base thereof disposed in suitably spaced relationship as shown, in part, in Figure 2 of the drawings. A plate 58 of substantially disk-like shape is secured to

the lowermost end of the supporting member 51 and extends substantially radially therefrom to contact the base of the basket 55 and to serve as a stiffening means therefor.

A sleeve bearing 59 is disposed internally of and adjacent the uppermost end of the hollow shaft 48, said bearing 59 providing a journal for the vertical shaft 60 which extends through the bore 61 of the hollow shaft 48 for rotation in concentric relation to the axis of said hollow shaft 48 and the center post 45. The end of the shaft 60 which projects beyond the upper end of the hollow shaft 48 has a tapered and squared portion 62 on which is secured, as by means of the bolt 63, an agitator 64 of the multiple-vane type.

An annular rim 65, which provides a safeguard against the possibility of the operator inadvertently inserting his hand between the upper end of the basket 55 and the tub 35 when the apparatus is operating, and also prevents the escape of the cleansing fluid from the tub 35 in the course of operation of the machine, is demountably secured to the upper end of the tub 35 as by means of the flexible retaining ring 66. The retaining ring 66 renders it possible to remove said annular rim 65 if, for any reason, it should be necessary to have access to the basket 55 or for the removal of the same from the tub 35.

The annular rim 65 is provided with a depending portion 67 which is bent downwardly so as to extend within the opening 56 in the upper end of the basket 55.

A substantially funnel-shaped annular member 68 is secured in any suitable fashion to the depending portion 67 of the annular rim 65 and extends upwardly therefrom to a point adjacent the cover 30 of the cabinet so as to aid in the introduction to the machine of the clothing or other articles to be laundered as they pass through the lid 69 of the cover 30. A weighted collar 70 which is advantageously disposed about the external periphery of the member 68 is provided to supply added weight to the assembly of operating elements mounted on the upper side of the spider 34 which will tend to reduce the extent of the swinging movement of the freely supported spider 34. This weight ring or collar 70 is located inwardly of the side walls of the basket 55 and hence immediately above the region where the greater portion of the clothes will be thrown when the basket 55 is revolved at high speed.

As will be apparent from an inspection of Figures 1 and 3 of the drawings, the driving mechanism for actuating the agitator 64 and the basket 55 is suspended from and mounted on the underside of the spider 34. Power is derived from an electric motor 71 which is secured to a bracket 72 which carries the motor on the underside of the casting 34. The motor is of the vertical type and is provided with an armature shaft 75 upon which is mounted a drive pulley (not shown). The motor drive pulley is arranged to drive a pulley 77 through a drive belt 82, which pulley 77 is carried on the power input shaft 88 of the transmission unit 78. The drive pulley of the motor (not shown) is also arranged to drive a pulley 79 associated with the basket 55 for driving the same, and it is also arranged to drive through the same endless belt 82 a pulley 80 which operates a pump unit 81.

The power input shaft 88 of the transmission unit 78 is arranged to change continuous rota-

tional movement into oscillatory movement in order to provide the necessary oscillatory drive for the agitator. The power input shaft 60 is provided with a spur gear 96 which meshes with a large gear 97 rotatably mounted upon a stub shaft 98 and maintained in proper endwise relation with respect thereto by means of a snap ring 99 which is adapted to engage an annular groove formed on the stub shaft 98. The gear 97 through the crank arm 100 operates a sector gear 101 which is meshed with a gear 102 rotatably mounted upon the shaft 60 to which the agitator 64 is attached.

The gear 102 is disposed in axially slidable relation with respect to the vertical shaft 60. The lower hub portion 103 of gear 102 is provided with a plurality of slots 109 extending substantially axially thereof and tapered slightly to fit over the end of a pin 110 which is mounted on the shaft 60 so as to extend radially therefrom. The gear 102 is movable axially of the shaft 60 by means of a fork 111 which registers with an annular groove 112 cut into the upper hub portion 113 of the gear 102 so as to engage or disengage one of the slots 109 in the lower hub portion 103 of the gear 102 with the radially disposed pin 110 on the shaft 60. The fork 111 is secured to a vertically extending rod 114 which is adapted to slide endwise in the bore 115 of the internal boss 116 formed in the lower casting 86 of the transmission case, and a sleeve 117 mounted in the upper casting 85 of the transmission case. The rod 114 is raised and lowered by a control mechanism which forms no part of the present application. It will be sufficient to say that horizontal movement of a cam bar 193 causes the upstanding rod 114 to be raised and lowered to thereby disengage and engage, respectively, the agitator drive gear 102.

The shaft 60 which, as previously described, is journaled within the bore 61 of the hollow shaft 48 is concentrically disposed within the center post 45 and extends downwardly within the bore 44 of the boss 39 through the spider 34 and into the transmission unit 78. The lower end of the shaft 60 is journaled in the bore 118 of a boss 119 depending from the lower casting 86. A steel ball 120 which is disposed in the inverted, conically shaped base 121 of the bore 118 of said boss 119 serves as a thrust bearing, thereby supporting the shaft 60 in proper endwise relation.

On the under-side of the top casting 85 of the case enclosing the transmission unit 78 and encircling the shaft 60 adjacent the point where it extends through the top casting 85 is a packing unit comprising an inverted cup-shaped holder 122 for retaining the packing 123 which serves to prevent the entrance of dirt, dust, or other substances into the transmission case, in which the several parts are immersed in a lubricating medium as well as to prevent leakage of the lubricating medium from the case. The packing 123 is retained in the cup-shaped holder 122 by means of a disk member 124 held in place by a compressed spring 125 urged thereagainst by a washer 126 disposed endwise of the shaft 60 by means of a pin 127 therein. A collar 128 is secured to the shaft 60 at a point just above that at which the shaft 60 extends through the top casting 85 of the casing enclosing the transmission unit 78 as by means of a set screw 129. The collar is provided with a depending skirt portion 130 which extends downwardly over the opening in the top casting 85 through which the shaft 60 passes. The collar 128 acts as a means for supporting the

hollow shaft 48 by virtue of the fact that the sleeve bearing 131 fits into the hollow shaft 48 at its lowermost end and is provided with an annular flange portion 132 which contacts the upper face of the collar 128.

A pulley 79 which as previously explained is driven from the motor 71 is rotatably mounted about the external periphery of the hollow shaft 48 by means of the bushing 133 which is press fitted into the pulley 79. The pulley 79 is retained in endwise relation to the shaft 48 in any suitable manner.

The particular clutch and braking mechanism by which the basket 55 is driven by the pulley 79 forms no part of the present invention, and for that reason, it will be sufficient to point out that the flange ring 142 carrying a ring of friction material 144 is mounted for limited axial movement on the hollow shaft 48 but is prevented from relative rotation therewith. The flange member 142 is carried on a yoke member 157 which is mounted for limited angular movement about a pivot pin 162 on an upstanding post 159 carried on the upper housing member 85 of the transmission unit. The yoke 157 is angularly moved about the pivot pin 162 by limited vertical movement of the rod 166 which is in turn moved by horizontal movement of a cam bar 209. A spring 163 acting against a washer 164 on the post 159 holds the yoke member 157 against the pivot pin 162.

Another coiled spring 170 surrounding the rod 166 normally biases the yoke 157 to its lowermost position, or, in other words, with the pulley 79 in driving engagement with the flange member 142. When the rod 166 is lifted upwardly by the cam bar 209, the flange member which acts as the clutch is lifted free of the pulley 79 thereby to disconnect the driving engagement with the hollow basket shaft 48. As the flange member 142 is raised upwardly, a braking action takes place between the brake disk 172 and an annular member 156 which is carried on the shank portion 146 of the flange member 142.

The filling and draining mechanism insofar as it is pertinent to the present invention will now be described. Referring to Figure 4, the inlets 176 and 177 supply hot and cold water to an automatic temperature controlled mixing valve 178. The outlet side of the mixing valve 178 connects with a hose 179 which is arranged to deliver water to the tub 35 through the weighted collar member 68. As shown in Figure 6 of the drawings, the delivery hose 179 is connected to a nozzle 276 mounted upon the inner periphery of the annular member 68, and disposed adjacent to the cover 30 the nozzle 276 is provided with a flared outlet end 277, the back wall of which cooperates with a substantially semi-circular vertically disposed flanged portion 278 to position the nozzle 276 so that its threaded portion 279 will extend through an aperture 280 in the annular member 68. A female connection 282 which is adapted to be secured to the threaded portion 279 of the nozzle 276 provides a means for connecting thereto the flexible hose 179.

The base 37 of the tub 35 is provided with a sump 180, the bottom of which connects with the pump 81 through the hose connection 181 leading to the inlet side 182 of the pump 81. The outlet or discharge side 183 of the pump 81 connects through a hose 184 to a drain or catch-basin (not shown). The pump unit 81 is arranged to be driven from the motor 71 in any convenient manner.

As will be apparent from Figures 1 and 4 of the drawings, substantially all of the operating and control mechanism of the automatic washing machine is supported within the cabinet in substantially floating relation. This mounting is effected by suspending the casting or spider 34 from the frame structure of the cabinet as by means of a plurality of suspension members 186. The spider or casting 34 is provided with a plurality of projecting lugs 187 to which the lower ends of the suspension members 186 are secured. Three such lugs 187 and a corresponding number of suspension members 186 are shown in the preferred form of the invention. Two of the suspension members 186 are disposed at corners of the cabinet, while the third suspension member 186 is positioned midway of the ends of the opposite wall of the cabinet.

A pair of angle members 188 disposed diagonally of the adjacent corners of the cabinet and secured to the web portion of the channels 22 provide means to which the upper ends of the two suspension members 186 disposed at adjacent corners of the cabinet may be secured. A mounting means 189 is shown as being attached to the web of the channels 22 at the right-hand side of the frame (as illustrated in Figure 4) to provide a means to which the upper end of the third of the suspension members 186 may be secured.

Each suspension member 186, which is shown in detail in Figure 5 of the drawings, comprises a pair of substantially spherical molded cushioning pads 190, one of which is secured to each end of the rod portion 191 as by means of the threaded studs 192. The studs 192 are provided with flat heads 193 which are molded into the cushioning pads 190 formed of rubber or other resilient moldable material. The threaded ends of the studs 192 are adapted to be threaded into the internal bore of the rod portion 191 to provide endwise adjustment of the suspension members 186, lock nuts 194 being provided to retain said studs 192 in their proper adjusted endwise relationship to the rod portion 191.

The mounting means 189 is provided with a substantially hemispherically shaped socket 195 in the face thereof to receive the substantially spherically shaped cushioning pads 190 of the suspension members 186. A cap member 196 of a shape corresponding to that of the socket 195 is secured to the face of the suspension means 189 by the bolt 197 and cooperate with said socket 195 to completely enclose the cushioning pads 190.

A similarly shaped hemispherically shaped socket 198 is formed in the underside of the lugs 187 of the casting 34, and having the base apertured as at 199 through which the studs 192 associated with the lowermost cushioning pad 190 may extend. A cap 200 cooperates with the socket 198 in the lugs 187 to completely enclose the cushioning pads 190 and is secured to said lugs 187 as by means of the bolts 201 (see Figure 4).

A substantially identical construction to that just described is associated with each of the remaining suspension members 186 thereby providing a free and flexible mounting for the spider or casting 34. This floating mounting with the weight ring located substantially opposite to the point from which the members 186 are suspended from the casing of the washing machine and high above the floating base or casting on which substantially all of the mechanism of the washing machine is mounted, substantially eliminates vibrations from being transmitted to the outer shell or casing of the washing machine and to the

floor or other support on which the washing machine is seated.

During operation of the washing machine, the tub 35 is first filled with soapy water and then the agitator 64 is oscillated through the transmission unit 78. This operation, when completed, is followed by a draining of the water from the tub 35 through the sump 180 and the hose 181, the pump 81 being used to discharge the water through the discharge hose 184. Thereafter, the basket 55 is rotated at high speed to extract the water from the clothes. It is at this time in the cycle of operation that trouble is usually encountered in machines heretofore known from excessive vibration. The machine of the present invention, however, substantially eliminates all vibration even though the clothes or other articles being washed are disposed in an unsymmetrical manner within the basket 55. Following the extraction operation, the steps may again be repeated except this time clear fresh water is used rather than soapy water in order to effect the rinsing of the clothes.

While we have shown a particular embodiment of our invention, it will, of course, be understood that we do not wish to be limited thereto since many modifications may be made, and we therefore contemplate by the appended claim to cover all such modifications as fall within the true spirit and scope of our invention.

We claim as our invention:

In a laundry machine, a casing, a platform within said casing spaced a substantial distance above the bottom thereof, a plurality of suspension links, means supporting said links on said casing adjacent the upper end thereof and yieldably restraining gyratory movement of said links about their upper ends, means suspending said platform from the lower ends of said links and yieldably restraining gyratory movement of said platform about said links, a fluid containing tub secured to said platform and extending upwardly therefrom, a clothes containing basket rotatably mounted on said platform within said tub, drive mechanism depending from the bottom of said platform, said tub having an annular rim extending over the top of said basket and terminating in a flange extending within said basket and above the top thereof and forming a non-rotatable clothes receiving opening for said basket, and an annular counterbalancing weight encircling said flange and secured to the outer periphery thereof and extending above the top of said basket and the region of the unbalanced mass of clothes therein.

PETER EDUARD GELDHOF,
LUTHER RINGER.
